UNITED STATES PATENT OFFICE.

SAMUEL E. MOWER, OF NEW HAVEN, CONNECTICUT, ASSIGNOR TO HENRY G. THOMPSON & SONS, OF SAME PLACE.

ELECTRIC-MOTOR MECHANISM.

SPECIFICATION forming part of Letters Patent No. 440,718, dated November 18, 1890.

Application filed May 10, 1890. Serial No. 351,242. (No model.)

To all whom it may concern:

Be it known that I, SAMUEL E. MOWER, of New Haven, county of New Haven, State of Connecticut, have invented an Improvement 5 in Electric-Motor Mechanism, of which the following description, in connection with the accompanying drawings, is a specification, like letters on the drawings representing like parts.

10 This invention relates to electric-motor mechanism especially adapted to be used on street-railway cars, and is an improvement upon the motor mechanism shown and described in another application, Serial No. 15 329,760, filed by me November 9, 1889.

My present invention relates more particularly to the speed-reducing mechanism, and has for its object to improve the construction of the same.

20 The particular features in which my invention consists will be pointed out in the claims at the end of this specification.

Figure 1 is a top or plan view of a car-axle having mounted upon it an electric-motor mechanism embodying my invention; Fig. 2, a sectional view of the motor mechanism shown in Fig. 1 on line $\alpha\alpha$; and Fig. 3, a sectional detail, to be referred to, on line $\gamma\gamma$, Fig. 1.

30 The yoke or arm A, supported on the car-axle A', provided with wheels A², the field-magnets a, secured to the said yoke, the armature a', secured to or forming part of the sleeve a², mounted upon the axle A', may be

35 substantially such as shown and described in my application referred to. The sleeve a² has secured to it, as by a key a³, (see Fig. 3), a gear a⁴, provided, as herein shown, with circumferential teeth to form a friction-gear.

40 The friction-gear a⁴ has co-operating with it, as herein shown, preferably four like friction-gears a⁵, keyed upon shafts a⁶, having bearings in a disk a⁷, provided with boxes a⁸, loosely fitted into recesses in the periphery of

45 the said disk. The friction-gears a⁵ are preferably loosely keyed to the shafts a⁶ to allow a slight lateral motion, and thus relieve the gears from side-thrust of the motor. The disk a⁷ may be made fast on the axle A' by a 50 suitable key, or it may be loose thereon.

Each shaft a⁶ has mounted upon it on the side of the disk opposite to that on which the friction-gears a⁵ are located a pinion b, provided with circumferential teeth to form friction-pinions, which are adapted to be brought into engagement, as will be described, with a friction-gear b', secured to the axle A', as by a key b². The loose boxes a⁸ and the disk a⁷ are encircled by a friction-strap b³, having its ends secured in suitable manner to a rod b⁴, 60 by turning which the said friction-strap may be made to move the loose boxes a⁸ radially toward the axle and clamp the shafts a⁶, the said boxes when the friction-strap is unloosened being normally held away from the disk 65 a⁷ by a cushion, herein shown as spiral springs b⁵, encircling screws or rods b⁶, extended through the boxes a⁸.

In operation the gear a⁴ is revolved continuously, and when the friction-strap is un- 70 loosened the friction-gears a⁵ are not revolved and the car-axle remains stationary; but if the driver or operator on the car turns the rod b⁴ to tighten or bind the friction-strap b³ and force the movable boxes a⁸ in toward the 75 axle the friction-gears a⁵ are brought into engagement with the gear a⁴, and the shafts a⁶ will be revolved, thus producing revolution of the car-axle through the friction-pinions b and gear b'.

The speed at which the car-axle is revolved may be controlled by regulating the pressure of the friction-strap b³ upon the movable boxes.

I have herein shown the friction-gear a⁴ as 85 engaged by four friction-gears a⁵; but I do not desire to limit myself to any particular number of the gears a⁵, as one or more may be used; but I prefer to employ the number herein shown.

90 I claim—

1. In an electric-motor mechanism, the combination, with an axle and a motor having its armature secured to a sleeve loosely mounted on said axle, of a speed-reducing mechanism 95 consisting of a gear fast on the armature-sleeve, a disk a⁷, mounted on the axle and provided with a recess in its periphery, a shaft a⁶, carried by said disk, a movable box for said shaft, a gear a⁵ on the shaft to co- 100

operate with the gear on the said shaft, and a gear fast on the axle, and a friction-strap encircling the movable box and disk, and means to engage said strap with the said disk, substantially as described.

2. In an electric-motor mechanism, the combination, with an axle and a motor having its armature secured to a sleeve loosely mounted on said axle, of a speed-reducing mechanism consisting of a friction-gear fast on the armature-sleeve, a disk ^{a7}, mounted on the axle and provided with recesses in its periphery, shafts ^{a6}, carried by said disk, movable boxes for said shafts, friction-gears ^{a5} on the said shafts to engage the friction-gear on the arma-

ture-sleeve, friction-pinions on the shafts ^{a6}, a friction-gear fast on the axle adapted to be engaged by the friction-pinions, a cushion interposed between the movable boxes and disk, a friction-strap encircling the movable boxes ²⁰ and disk, and means to engage said strap with the said disk, substantially as described.

In testimony whereof I have signed my name to this specification in the presence of two subscribing witnesses.

SAMUEL E. MOWER.
